INVENTOR

SOLOMON SACHS
BY
Maurice Block
ATTORNEY

UNITED STATES PATENT OFFICE.

SOLOMON SACHS, OF NEW YORK, N. Y.

PORTABLE PHONOGRAPH.

Application filed March 3, 1924. Serial No. 696,446.

To all whom it may concern:

Be it known that I, SOLOMON SACHS, a citizen of the United States of America, residing at New York city, county and State 5 of New York, have invented certain new and useful Improvements in Portable Phonographs, of which the following is a specification.

This invention relates to portable phonographs and in particular to a type adapted when closed to simulate the flat type of pocket camera.

A particular object of the invention is to provide a phonograph of this character in 15 which the parts may be carried inside the phonograph and which when set up will operate efficiently.

Another important object is to provide a phonograph of this character which makes 20 use of the container as a sound box, in other words, the portion or space which is occupied by the various parts of the phonograph in transportation may be used as an amplifier when the phonograph is set up for operation.

A further object is to produce a tone arm which will close the compartment in the phonograph when the same is being carried.

Other objects are to provide a portable 30 turn table, and tone arm, and reproducer, which can be carried inside the phonograph when the same is not in use.

Referring to the drawing wherein I have shown a preferred embodiment of my invention,

Fig. 1, is a top plan view of a portable phonograph made up to represent the conventional flat pocket camera, the parts being shown dotted,

Fig. 2, is a view in side elevation, the parts thereof being shown in section, of the phonograph in position for use, the parts thereof being shown in their relative operating position,

Fig. 3, is a section on the line 3—3 of Fig. 2, and shows the interior of the tone arm,

Fig. 4, is a top plan view of the motor end of the phonograph showing a turn table in open position thereon, the dot and dash lines showing the position assumed by the arms of the turn table when the same are folded,

Fig. 5, is a view in perspective of a modified form of mounting for the reproducer 55 in this instance, the tone arm being dispensed with and an expandible supporting

arm being used together with a slidable side piece for the phonograph,

Fig. 6, is a section on the line 6—6 of Fig. 5,

Fig. 7, is a section on the line 7—7 of Fig. 5, and

Fig. 8, is a section on the line 8—8 of Fig. 5.

Referring to the drawing in detail, 65 5 indicates the housing for the phonograph parts which is so shaped as to simulate the pocket type of flat camera having the rounded ends 6, and a carrying strap 7. In one end of the housing or container 5, there is fixed a 70 suitable motor 8, the shaft 9 of which projects up through the top of the casing to receive a turn table 10, upon which may be mounted the usual record 11.

The reproducer 12, is carried on the end 75 of the tone arm 13, through the medium of an inwardly extending flange 14, in said tone arm in which the tubular portion 15 of the reproducer frictionally fits. The tone arm has formed in one end thereof, the vertical 80 pipe 16, the lower end of which is beaded as at 17 to limit the downward movement of the pipe in the casing opening 18.

This opening 18 leads into the storage 85 space for the parts and when the parts are in operating position, it can be seen that this space will act as an amplifying chamber for the sounds emitting from the tone arm 13, the end of the tone arm is suitably rounded to match the rounded end 6 of the casing 90 5 so that when the same is placed in position against the offset 19, in the motor housing, the same will completely close the side of the phonograph and will retain in the sound box the reproducer 12 and turn table 10. 95

The tone arm is provided with suitable deflectors 20, opposite the openings therein so that the tone is conveyed directly into the sound box.

The turn table is composed of a suitable 100 disk 21 having a fixed arm 22, and two pivoted arms 23, the latter of which when not in use may be folded down parallel to the arm 22 so that it can be seen that the turn table will occupy little space and may 105 be stored in the sound box as shown in Fig. 1.

It is apparent also, that the loose connection of the pipe 16 in the casing 5 permits of vertical movement of the reproducer 12, 110 while the bead 17, permits of rotary movement of the reproducer. This combination

provides the universal movement necessary to efficient operation of a reproducer.

In Fig. 5, I have shown a method of supporting the reproducer which consists in 5 providing the housing 5 with a sliding side member 24, which normally closes the side of the empty portion of the phonograph, in this instance, this unoccupied portion not being used as a sound box. At the end of 10 this slide 24, I provide a bracket 25 into which the end of a telescopic arm 26 is retained, the forward end thereof being grooved annularly as at 27 and being adapted to fit into an extended tube portion 28 of the reproducer 12, this tube portion being provided with an opening 29 through which passes a spring pressed pin 30, the pin engaging the groove 27 to hold the reproducer in position on the end of the arm. The 20 reproducer carries, in this instance, the sound box or amplifier which is made up of a hemi-spherical shell member 31 of celluloid or the like, having an extended neck 32 which fits into the usual opening or tube 25 15 of the reproducer. The amplifier is provided with an integral perforated cover 33, having suitable openings 34 therein. A disk member 35 is disposed beneath the cover 33 and is revolvably held thereagainst through 30 the medium of a thumb nut 36, this disk being also provided with openings to match the ones formed in the cover, so that a revolving movement of the disk will vary the volume of the sound emitted.

35 In this construction, it is evident that the amplifier may be made shallow enough to fit into the housing and the supporting arm 26 may be also telescoped so that it may be

placed in the housing together with the reproducer.

The motor is of a common but compact type and may be readily wound with a suitable key.

In Fig. 1, when the tone arm has been placed in the position shown to close the 45 opening of the casing, I may provide suitable latch members 37 to retain the same in this position.

It will be seen therefore, that I have provided a portable phonograph which can be 50 carried in the pocket after the manner of the pocket camera, and one which will have few parts, which may be quickly assembled and will operate efficiently.

Having described my invention, what I 55 claim is:

1. A portable phonograph comprising a flat camera-like casing, a sound amplifying chamber in said casing having an open mouth, a tone arm for said phonograph, said tone arm when not in use being adapted to 60 serve as a closure for the mouth of said chamber.

2. A portable phonograph comprising a casing having a portion constituting a 65 sound amplifying chamber terminating in an open mouth, said casing having an opening through one side thereof in communication with said sound amplifying chamber, and a tone arm communicating with said 70 chamber through said opening and adapted to serve when not in use as a closure for the mouth of said chamber.

In testimony whereof I hereunto affix my signature.

SOLOMON SACHS.
